Primary Examiner — Christy Nemeth(74) *Attorney, Agent, or Firm* — Wenderoth, Lind & Ponack, L.L.P.(57) **CLAIM**

The ornamental design for a power module, as shown and described.

DESCRIPTION

FIG. 1 is a top, front perspective view of a power module according to a first embodiment;

FIG. 2 is a bottom view thereof;

FIG. 3 is a rear elevation view thereof;

FIG. 4 is a left side elevation view thereof;

FIG. 5 is a right side elevation view thereof;

FIG. 6 is a front elevation view thereof;

FIG. 7 is a top view thereof;

FIG. 8 is a top, front perspective view of the power module according to a second embodiment;

FIG. 9 is a bottom view thereof;

FIG. 10 is a rear elevation view thereof;

FIG. 11 is a left side elevation view thereof;

FIG. 12 is a right side elevation view thereof;

FIG. 13 is a front elevation view thereof; and,

FIG. 14 is a top view thereof.

The broken lines in the drawings are for the purpose of illustrating portions of the power module that form no part of the claimed design.

1 Claim, 14 Drawing Sheets(56)
